Primary Examiner — Sharon S Oum*(74) Attorney, Agent, or Firm* — McGarry Bair PC(57) **CLAIM**

The ornamental design for a ceiling fan motor housing as shown and described.

DESCRIPTION

FIG. 1 is a top perspective view of a ceiling fan motor housing in the environment of a ceiling fan, showing my new design.

FIG. 2 is a top perspective view of the ceiling fan motor housing with the ceiling fan environment of FIG. 1 removed. FIG. 3 is a top view thereof.

FIG. 4 is a bottom view thereof; and,

FIG. 5 is a front side view thereof with rear, left, and right side views being identical thereto.

Portions of the ceiling fan and the ceiling fan environment are shown in broken lines. Portions shown in broken lines form no part of the claimed design.
